UNITED STATES PATENT OFFICE.

ALLEN A. BOWSER, OF FORT WAYNE, INDIANA, ASSIGNOR TO S. E. BOWSER & COMPANY, INCORPORATED, OF FORT WAYNE, INDIANA, A CORPORATION OF INDIANA.

TANK-FILLING APPARATUS.

1,107,886.

Specification of Letters Patent. Patented Aug. 18, 1914.

Application filed May 31, 1910. Serial No. 564,102.

To all whom it may concern.

Be it known that I, ALLEN A. BOWSER, a citizen of the United States, residing at Fort Wayne, in the county of Allen and State of Indiana, have invented certain new and useful Improvements in Tank-Filling Apparatus, of which the following is a specification.

This invention relates to tank filling apparatus, and has for its primary object to provide an improved construction, combination and arrangement of parts in a storage system for a number of oils of different kinds.

One object of the invention is to provide improved means for introducing the different oils into their respective receptacles directly from the barrels in which they are received.

Another object is to provide improved means for disposing the barrels into suitable positions for emptying directly into the respective oil receptacles.

Another object is to provide improved means for venting the several tanks or receptacles in an oil storage system in such manner as to prevent the intermixture of vapors from different tanks and the formation of explosive mixtures, while at the same time permitting the introduction of air into said tanks to take the place of the oils drawn therefrom.

Other and further objects will appear in the specification and be more specifically pointed out in the appended claims, reference being had to the accompanying drawings exemplifying the invention, and in which.

Figure 1 is a perspective view of a tank filling apparatus for oils constructed and arranged in accordance with the principles of this invention. Fig. 2 is a medial longitudinal section through one of the tank units shown in Fig. 1. Fig. 3 is a top plan view of the tank shown in Fig. 2. Fig. 4 is a perspective view of one of the tanks or receptacles on an enlarged scale, showing the barrel dash and fill pan devices, the suction and return pipes, together with the pump, not being shown in this figure. Fig. 5 is a front elevation of the barrel dash detached. Fig. 6 is a side elevation of the same. Fig. 7 is a bottom plan view of the same. Fig. 8 is a detail elevation of a portion of the vent

header with a vent-valve shown in section connected thereto. 55

Referring more specifically to the drawings, and first to Fig. 1, the storage apparatus proper comprises a plurality of tanks, such as tanks, 1, 2, 3, 4, 5 and 6. These tanks are preferably rectangular parallel- 60 epipedons arranged with their lateral walls abutting one against another, and each provided with a manhole cover hermetically sealed about its circumferential edge to the top wall and indicated diagrammatically at 65 7 in Fig. 1. In each of said manhole covers is provided a fill opening, the fill openings in the several tanks being in alinement. Suspended from each of the manhole covers 7 in any suitable manner (see Fig. 2) is a fill 70 tube 8 which reaches to within a short distance of the bottom of the receptacle or tank and below the intake end of a suction pipe 13 so that the passage of vapors from said tube 8 is prevented by sealing its lower end with 75 fluid. Said tube 8 and pipe 13 are hermetically sealed to the top wall. Suitably mounted above the tanks and preferably supported thereby, is a barrel track extending from one end of the series of tanks to the other, said 80 track being constituted by rails 9 and 10 carried by standards or uprights 11 and 12. By means of this barrel track, a barrel having been placed thereon at one end may be rotated therealong until over the fill opening of the tank into which it is to be emptied, 85 when the bung being removed from the barrel, the oil is permitted to discharge into the tank wherein it is stored until drawn therefrom for use. As shown in Fig. 2, each fill 90 pipe 8 is provided at its upper end with a fill pan 8' for receiving the direct discharge from the barrel. Said fill pan is preferably provided with a removable screen (not shown in the drawings). The suction pipe 95 13 is provided adjacent the bottom of the tank with a strainer 14, the intake opening of said suction pipe being disposed above the openings in the lower ends of the fill pipe 8 and return pipe 17, thus maintaining 100 a fluid seal about the openings in said pipes. Any suitable pumping device for removing the oil from the tank may be connected up with said suction pipe, such as a pump 15 (see Fig. 1) arranged on the floor above the 105 storage tanks 1 to 6, the embodiment shown

herein illustrating the application of the invention to a system having the storage tanks arranged in a cellar and a series of pumps connected respectively with said tanks on the floor above, there being but one of these pumps indicated in the drawing.

In Fig. 1 a plurality of drip pans 16 are disposed respectively beneath the discharge outlets of the pumps 15, said drip pans 10 communicating by return pipes 17 with the respective storage tanks or receptacles. Each of the return pipes 17 is hermetically sealed to the top wall of its tank. A vent opening 18 in the top wall of each storage tank communicates through a pipe 19 with the open air distant from the storage tanks, said pipe 19 being hermetically sealed to the top wall about the edge of said opening. As shown in Fig. 1, each vent pipe 19 connects with a common header 20, said header 20 leading in turn to a vertical up-take 21, which, in this embodiment, is provided with a double goose-neck 22 without the building in which the oil is stored, said goose-neck being provided with screens (not shown) for the purpose of preventing the passage of fire and also adapted to keep out rain or moisture. In each vent pipe 19 between the tank and the common header 20 is placed a valve, in a casting 23 of suitable construction for preventing the vapors from different tanks being intermingled through the header 20, thus preventing the production of explosive mixtures and all possible spontaneous combustion which might be caused by the chemical action between different vapors.

Referring now to Fig. 8, each valve casting 23 comprises an upper threaded portion 36 by means of which it is connected up with a T-coupling 37 to the header 20, and a lower threaded portion 38 by which it is connected to one of the vent pipes 19. Intermediately of said portions, the valve casting is provided interiorly with an annular shoulder or neck 39 forming a valve seat for the valve 40 which is movably mounted preferably by a valve stem 41 slidably mounted in an apertured partition 42 through which the vapors pass from the vent pipe 19. It will be noticed that the valve 40 is free to open upwardly to permit the displacement of air and vapor when the tank is being filled, but is forced shut to prevent any vapor from the header passing down into the tank. In order to provide means for permitting the entrance of air into each tank to displace the fluid drawn therefrom, the valve casting 23 is provided below the valve 40 with a lateral channel 42¹ controlled by a ball valve 43 which permits air to flow inwardly and prevents vapors flowing outwardly into the room. A screen 44 provides a safeguard 65 against fire.

In order to provide simple and efficient means for raising and lowering the barrel to and from the barrel track extending across the series of tanks, a hoisting cradle consisting preferably of track sections 24, 25 are pivotally connected respectively with the rails 9 and 10 already referred to. The sections 24, 25 are joined together at their outer ends, the outer portion of said cradle being deflected at an angle to the portion 75 adjacent the tank 1, so as to adapt said cradle to receive a barrel 26 when said cradle is in lowered position, and to maintain said barrel in position while it is being hoisted to the level of the barrel track. 80 Connected to the outer end of the cradle is a hoisting chain 27 preferably leading to a hoisting device 28 suspended from the floor 29 of the room above.

Referring now to Figs. 4, 5, 6 and 7, a 85 device for facilitating the emptying of barrels into the different tanks is provided in the form of a barrel dash comprising a shield or plate 30 with its lateral edges 31 and 32 bent to form a substantially trough-shaped structure. Said plate 30 has rigidly secured thereto a deflector portion 33 conforming above with the plate 30 but deviating therefrom below into a circularly bent portion 45 for deflecting the oil in the fill 90 pan over which it may be disposed. Mounted upon the lateral edges 31 and 32 are angle brackets 46 and 47 which when the barrel dash is set up on the track, are adapted to engage either edge of the rails 100 9 and 10 and to hold the barrel dash securely. In this position, (see Fig. 4), the portion 45 overhangs and discharges into the fill pan 8'. A collar or shield 35 extends around and is carried by the fill pan 8'. Owing to the resiliency of the metal from 105 which the barrel dash is constructed, said barrel dash may be installed in or removed from position by turning the same to swing the angle plates 46 and 47 into and out of 110 engagement with the rails 9 and 10.

What I claim is:

1. A tank filling apparatus comprising a plurality of tanks having alined fill openings, a barrel track extending across said tanks over the fill openings, and an elevating cradle pivotally mounted at one end of the track and comprising portions inclined to each other at an angle greater than a right angle so that the outermost portion 120 will lie substantially flat on the floor to receive barrels.

2. A tank filling apparatus comprising a plurality of tanks having alined fill openings, a barrel track extending across said 125 tanks over said openings, a cradle consisting of track members pivotally connected to the rails of the barrel track and joined at the outer end, the said track members being bent so that a portion of the cradle will lie 130

flat on floor to receive a barrel, and means to elevate the outer end of the cradle so that the other portion thereof will be level with the barrel track.

5 3. In a tank filling apparatus, the combination with a tank provided with a fill pan connected to said tank, a barrel-track mounted on said tank, and means for holding the barrel against movement along the track, said means comprising a shield having a plate to intercept oil discharged from the bunghole of a barrel while it is being turned to bring the bunghole directly over said fill pan.

10 4. In a tank filling apparatus, the combination with a tank provided with a fill pan, of a barrel track extending across the tank, and a barrel dash discharging into said fill pan, said dash being provided with abutments adjacent the track for engaging and holding the barrel against movement along the track while it is being turned.

15 5. In a tank filling apparatus, the combination with a plurality of tanks, each provided with a fill pan discharging thereinto, a barrel track mounted over said tanks, and

a barrel dash and abutment carried by said track and movable into a position above the fill pan leading to any of said tanks.

6. In a tank filling apparatus, the combination with a plurality of tanks having aligned fill openings, of a barrel track extending across said tanks over said fill openings, an elevating cradle pivotally mounted at one end of the track and having portions inclined to each other at an angle greater than a right angle, one of which is adapted to lie flat on the floor to receive a barrel, the cradle being raised until the other portion is level with the track to discharge a barrel, and a barrel dash and abutment supported by the track and movable into position above the openings leading to any of said tanks.

In testimony whereof I have signed my name to this specification, in the presence of two subscribing witnesses, on this 26th day of May, A. D. 1910.

ALLEN A. BOWSER.
